UNITED STATES PATENT OFFICE.

WILLIAM L. BLISS, OF BROOKLYN, NEW YORK.

INCANDESCENT ELECTRIC LIGHTING.

1,022,057.

Specification of Letters Patent.

Patented Apr. 2, 1912.

Application filed October 20, 1905. Serial No. 283,570.

To all whom it may concern:

Be it known that I, WILLIAM L. BLISS, a citizen of the United States, residing at New York city, borough of Brooklyn, New

5 York, have invented certain new and useful Improvements in Incandescent Electric Lighting, of which the following is a full, clear, and exact description.

My invention relates to improvements in 10 systems and apparatus for incandescent electric lighting.

It is particularly applicable to what is termed turn-down lamps, but may be employed for other purposes. Such lamps are 15 usually provided with multiple filaments and luminosity is varied by changing the circuit arrangement of the filaments.

In the preferred embodiment of my invention the arrangement of the filaments 20 controlled by an electro-magnetically operated switch and the switch is in turn adapted to be operated from a distant point.

Figure 1 is a side view of a lamp and vertical section of a socket embodying improvements of my invention. Fig. 2 is an end view of the socket with the lamp removed. Fig. 3 is a similar view of the insulating block in which the parts are mounted. Fig. 4 is an end view of the lamp removed from 30 the socket. Fig. 5 shows two detailed views of a short-circuiting contact. Fig. 6 shows two detailed views of the main contact having a branch which co-operates with the short circuiting contact. Fig. 7 is a dia- 35 grammatic view of a system embodying my invention. Fig. 8 is a side view of a modified structure in which the short-circuiting mechanism is embodied in an auxiliary socket secured in a regular socket and provided with terminals of slightly different 40 type. Fig. 9 is a side view of this auxiliary socket. Fig. 10 is a detail showing the polarized relay and circuit. Fig. 11 is a sectional view of the relay and armature.

45 1 indicates the lamp bulb.

2 and 3 are high and low resistance filaments. These are preferably arranged to be normally connected in series, so that as the high resistance filament 2 will take the 50 greater amount of energy, it only will give forth appreciable light.

4 is the central terminal.

5 is an intermediate annular terminal common to both filaments.

55 6 is a screw-threaded outer terminal for the main low resistance filament 3.

7 is a block of insulating material. 8 is the main spring contact secured to this block and connected to one branch X of the lighting circuit.

60 9 is an electro magnet mounted in the insulating block and having a polarized armature 10.

11 is a screw-threaded terminal. The other branch Y of the lighting circuit contains the coils of the electro magnet 9 and is 65 connected to the terminal 11.

A and B are the mains of a direct-current energizing circuit.

C is the pole-changing switch by which 70 the branches X and Y are adapted to be connected to the mains A and B. Normally the current flowing energizes the magnet 9 and draws the armature 10 to the left, so that the current flows through the branches 75 X and Y, passing from X through contact 8, terminal 4, high resistance filament 2, terminal 5, low resistance filament 3, terminal 6, terminal 11, through the coils of the electro-magnet to Y, so that only the high resistance filament gives appreciable light.

80 12 is a branch of the main contact 8 in the form of a spring finger.

13 is an arm of the short-circuiting member, having one end located adjacent the end 85 of the arm 12. The other arm 14 contacts with the annular terminal 5 of the lamp.

15 is a tip carried by the polarized armature 10, having its path of movement in line with the end of the arm 12.

90 16 is a case surrounding the operating parts of the mechanism.

When the direction of the current through the branches X and Y is reversed by the 95 pole-changer C, the magnetization of the magnet 9 is reversed and draws the armature 10 to the right. The tip 15 forces the end of the arm 12 against the end of the arm 13, and thus short-circuits the high resistance filament 2, so that the low resistance filament 3 receives the principal current and is rendered highly incandescent. The current then flows from Y, through the magnet coils, terminals 11 and 6, filament 3, terminal 5, arm 14, arm 13 and finger 12 100 to X.

17 is a socket of the ordinary type, provided with the ordinary socket-button 18 and switch.

110 19 is an intermediate or auxiliary socket adapted to carry mechanism similar to the mechanism thus far described, and which

may serve to install lamps and the system of my invention without replacing the ordinary sockets in use.

20 is the central terminal.

5 21 is a screw-threaded terminal for connection with the socket 17.

The lamp 1' is shown with a central threaded socket 4' connected to the low resistance filament 3, instead of the flat plate 10 socket 4. The annular terminal 5' is a common terminal for the two filaments. The outer terminal 6' is a plain ring constituting one terminal of the high resistance filament 2. The central terminal 8' of the 15 socket, coöperates with the terminal 4' and the lateral terminal 11' coöperates with the terminal 6'. It will thus be seen that the parts are mechanically the reverse of those shown in Fig. 1.

20 With the socket shown in Fig. 1, an ordinary single filament lamp having a central plate terminal and outer screw-threaded terminal may be employed and lighted up or turned out when the current is flowing in 25 either direction.

The auxiliary socket 19 may be employed with ordinary sockets having central spring contact and an outer screw-threaded terminal. The lamp 1' may be employed in 30 any socket having a central threaded post and a contact adapted to coact with an annular terminal. It will be obvious from this that the lamp 1 might be wired similar to the lamp 1', so as to be operable on the low 35 resistance filament in an ordinary socket. It will also be obvious that the auxiliary socket 19 might be constructed with its lamp terminals similar to those of Fig. 1. This lamp and system has particular utility in lighting 40 where it is desired to employ a number of lamps and which at times are required to give less light than at others.

Any number of lamps may be controlled simultaneously by a single switch, as indicated in Fig. 7. The lamps may all be 45 normally connected so that each one will give its maximum light, and so that all may be turned down simultaneously. The lamps might also be arranged so that normally part 50 of them would give their maximum light, while others would give their minimum

light. The operation of the pole changer in such cases would turn down some of the lights and turn up others. In a system embodying sockets of my invention, if ordinary 55 single filament lamps are employed, the operation of the pole changer would not affect the lights. The principal advantage of the invention is that it affords opportunity to control the turning up and down of one or 60 more lamps from a distance.

What I claim is:

1. An incandescent electric lighting apparatus comprising a base, a main spring contact having a branch arm, a short-circuiting 65 spring contact having an arm, and magnetically operable means for connecting said arms.

2. In an incandescent lamp socket, a base, a spring arm having a centrally located terminal, a second spring arm having an eccentrically located terminal, and an annular terminal. 70

3. In an incandescent lamp socket, a base, a spring arm having a terminal disk, a second spring arm having a terminal disk, and a spring branch integral with each arm, 75 said branches being adapted to be connected.

4. In an incandescent electric lighting apparatus, a socket member having a screw-threaded terminal and two spring arm contacts, and a removable lamp having two filaments connected in series, a screw-threaded terminal connected to one filament, a plate connected to the other filament and an annular terminal common to both filaments, said screw-threaded socket terminal engaging the screw-threaded lamp terminal, and said contacts engaging said plate and said annular terminal respectively. 80

5. In an incandescent lighting system, a distributing circuit, a lamp socket connected thereto and having three contacts for engagement by lamp terminals, and a polarized relay switch in said socket for connecting 95 two of said contacts when the current flows in one direction in the circuit.

WILLIAM L. BLISS.
